(57) **CLAIM**

The ornamental design for a display screen with graphical user interface, as shown and described.

DESCRIPTION

FIG. 1 is a front view of a display screen with graphical user interface showing our new design;

FIG. 2 is a front view of the display screen with graphical user interface of FIG. 1 shown on a device;

FIG. 3 is a front view of a display screen with graphical user interface showing an alternative embodiment of our new design; and,

FIG. 4 is a front view of the display screen with graphical user interface of FIG. 3 shown on a device.

The broken line showing of the display screen, device and remainder of the graphical user interface is for environmental purposes only and forms no part of the claimed design.
